UNITED STATES PATENT OFFICE.

ROBERT E. L. DAGGS AND AZRO J. DAGGS, OF PHOENIX, ARIZONA TERRITORY.

LOG-CARRIER.

SPECIFICATION forming part of Letters Patent No. 578,218, dated March 2, 1897.

Application filed July 14, 1896. Serial No. 599,167. (No model.)

To all whom it may concern:

Be it known that we, ROBERT E. L. DAGGS and AZRO J. DAGGS, citizens of the United States, residing at Phoenix, in the county of 5 Maricopa and Territory of Arizona, have invented a new and useful Log-Carrier, of which the following is a specification.

The invention relates to improvements in log-carriers.

10 The object of the present invention is to improve the construction of log-carriers and to provide a simple and comparatively inexpensive one which will be strong and durable and which will enable heavy logs to be easily 15 handled and carried.

The invention consists in the construction and novel combination and arrangement of parts hereinafter fully described, illustrated 20 in the accompanying drawings, and pointed 25 out in the claims hereto appended.

In the drawings, Figure 1 is a perspective view of a log-carrier constructed in accordance with this invention, one of the wheels being removed. Fig. 2 is a longitudinal sectional view of the same. Fig. 3 is a transverse 25 sectional view.

Like numerals of reference designate corresponding parts in all the figures of the drawings.

30 1 designates an axle having carrying-wheels 2 journaled on its ends and having hounds 3 secured to it at the inner terminals of its journals. The axle, which is arched intermediate of its ends, and the hounds, which extend forward 35 from the axle, are preferably constructed of tubular metal, and a pole or tongue 4 is clipped to the hounds and similarly secured to a tubular cross-piece 5, extending transversely of the hounds and located in advance 40 of the wheels. This construction forms a truck, to which a log to be carried is connected by means hereinafter described.

A substantially vertical standard 6 is located centrally above the drop-axle and is 45 supported by tubular braces 7 and 8, disposed in pairs at each side of the log-carrier. The braces 7 have their lower terminals extended forward and clipped to the upper faces of the hounds, and the lower terminals of the braces 50 8 are similarly secured to the upper face of

the axle, preferably by the clips employed for attaching the rear terminals of the hounds to the same. The lower end of the standard is mounted on a block 9, which is arranged on and centrally clipped to the arched portion 55 of the axle, and the upper end of the standard is connected with blocks 10 and 11, disposed above and below the braces 7 and 8. Each pair of braces 7 and 8 is preferably constructed of a single piece of tubular metal, 60 and a seat 12, for the accommodation of the driver, is mounted on the braces and is provided with a spring 13, which is secured to the upper block 10. Foot-rests 12^a are mounted on the braces 7, at opposite sides thereof, in 65 convenient position for the feet of the driver.

Within the standard, which is provided with a vertical opening, is adjustably fulcrumed an operating-lever 14, which is provided a short distance from its front end with 70 a perforation receiving a pin 15, adapted to engage any one of a series of perforations 16 of the sides of the standard, whereby the operating-lever may be raised or lowered to accommodate the carrier to the logs to be carried. The operating-lever is provided in front and in rear of the standard with automatically-operating log-engaging devices 17 and 18, consisting of tongs adapted to engage 75 a log below the bulge thereof and provided at the lower terminals of their members with inwardly-extending points engaging the log. The sides or members of the front tongs are pivoted adjacent to their upper ends, and one of the sides or members is provided with 80 an opening 19, through which passes the other side or member, and this construction strengthens the tongs and limits the swing of the sides or members, whereby the lower ends of the latter will be held separated sufficiently to enable a log to spread them readily. When the tongs are lowered to a log by 85 swinging the rear end of the operating-lever upward, they open automatically and engage the log below the bulge or central portion 90 thereof. The upper terminals of the sides or members of the tongs are connected by link-bars 20 with an adjustable hanger 21, and the latter, which is oblong, receives the front 95 end of the lever and is provided with a se- 100

ries of perforations for the reception of a pin 22, which adjustably secures the hanger to the lever.

The link-bars 20 and the upper arms of the 5 tongs constitute a toggle connection and cause the lower engaging portions of the tongs to clasp a log firmly when the front portion of the operating-lever is swung upward.

The rear tongs, which are constructed similar to the front tongs, are provided at one 10 side or member with an opening 23 for the reception of the other member, and the upper arms of the members are connected by links 24 with a hanger 25. The hanger 25 is 15 oblong to receive the operating-lever, and it carries a roller 26, journaled within the upper portion of the hanger and arranged to ride on the upper edge of the operating-lever. The rear tongs are capable of adjustment 20 longitudinally of the rear portion of the lever to position them properly with relation to a log.

To carry a log, the front tongs are lowered into engagement with the same, and the rear 25 portion of the operating-lever is swung downward, thereby raising the front portion of the log clear of the ground. The operating-lever is of sufficient length to enable the front portion of the log to be readily lifted by a 30 comparatively slight pressure on its rear end, and the front portion of the log is locked in its elevated position by engaging the rear tongs with the log. The front portion of the log is suspended beneath the arched axle and 35 the rear portion of the log drags upon the ground.

Draft-chains 27, which are connected at their front terminals to a doubletree 28, have their rear terminals secured to the front tongs 40 at opposite sides thereof, whereby a straight forward draft is exerted on the log at a most advantageous point. Singletrees are connected with the ends of the doubletree in the usual manner, and the doubletree is suspended 45 adjustably from the front ends by a chain 29 to prevent the whiffletrees from dropping to the ground.

The axle is provided with a centrally-arranged hook 30 and is connected by a centrally-arranged chain 31 with the draft mechanism. The chain 31 is attached near its front 50 end to the chain 29, and this chain 31 connects the draft mechanism directly with the axle when no log is being carried and prevents the log-carrier from moving rearward when loading 55 a log on the side of a hill.

The draft-animals are connected with the front end of the pole or tongue by a neck-yoke in the usual manner.

60 It will be seen that the log-carrier is simple and comparatively inexpensive in construction, that it possesses great strength and durability, and that it enables a log to be readily handled. It will also be apparent that as the 65 front portion of a log is suspended centrally beneath the axle and as the draft is arranged

centrally on the log and not above the same it may be readily dragged over the ground.

Changes in the form, proportion, and minor details of construction may be resorted to 70 without departing from the principle or sacrificing any of the advantages of this invention.

What we claim is—

1. In a log-carrier, the combination of a 75 truck, a substantially vertical standard mounted on the truck, a lever disposed longitudinally of the truck and fulcrumed intermediate of its ends on the standard, and log-engaging devices connected with the lever in 80 advance and in rear of the pivotal point, substantially as described.

2. In a log-carrier, the combination of a truck, a standard mounted on the truck and disposed substantially vertically, a longitudinally-disposed operating-lever fulcrumed adjacent to its front end on the standard, front and rear hangers mounted on the operating-lever in advance and in rear of the fulcrumming-point, the front hanger being pivoted to the lever, and the rear hanger being 90 slidably mounted thereon and capable of movement longitudinally thereof, and front and rear log-engaging devices connected with the hangers, substantially as described. 95

3. In a log-carrier, the combination of a truck, a standard mounted on the truck and disposed substantially vertically, a longitudinally-disposed operating-lever fulcrumed adjacent to its front end on the standard, 100 front and rear hangers mounted on the operating-lever in advance and in rear of the fulcrumming-point, the front hanger being pivoted to the lever and the rear hanger being slidably mounted thereon and capable of 105 movement longitudinally thereof, front and rear tongs, each composed of two sides or members, one of the sides being provided with an opening receiving the other side and limiting the swing thereof, whereby the tongs 110 are held sufficiently open to enable them to engage a log automatically, and links connecting the upper arms of the tongs with the hangers and forming a toggle connection, substantially as described. 115

4. In a log-carrier, the combination of a truck, a vertical standard mounted thereon and provided with a longitudinal opening, an operating-lever adjustably fulcrumed, at a point intermediate of its ends in an opening 120 of the standard, rectangular hangers mounted on the lever and located in advance and in rear of the standard, a pin adjustably pivoting the front hanger to the lever, a roller mounted in the upper portion of the rear 125 hanger and arranged to ride on the upper edge of the operating-lever, and front and rear log-engaging devices connected with the hangers, substantially as described.

5. In a log-carrier, the combination of a 130 drop-axle, wheels journaled thereon, hounds extending forward from the axle, a pole con-

nected with the hounds, a substantially vertical standard centrally mounted on the axle, braces disposed in pairs at the sides of the carrier, connected at their upper portions to 5 the top of the standard and having their lower terminals secured respectively to the axle and to the hounds, a lever fulcrumed on the standard, and log-engaging devices connected with the lever and located in advance and in rear 10 of the fulcruming-point, substantially as described.

6. In a log-carrier, the combination of a truck, an operating-lever fulcrumed intermediate of its ends and disposed longitudinally 15 of the truck, front and rear log-engaging devices connected with the lever and located in advance and in rear of the fulcruming-point, draft-chains connected with the front log-engaging devices at opposite sides of a log, and 20 a doubletree connected with the draft-chain, substantially as described.

7. In a log-carrier, the combination of a truck, an operating-lever disposed longitudinally thereof and fulcrumed intermediate of its ends, front and rear log-engaging devices 25 depending from the lever, draft-chains connected with the front log-engaging devices at opposite sides of a log, a doubletree connected with the front ends of the draft-chains, a centrally - arranged chain connected with the 30 truck and with the doubletree, and a chain suspending the doubletree from the truck, substantially as described.

In testimony that we claim the foregoing as our own we have hereto affixed our signatures 35 in the presence of two witnesses.
